UNITED STATES PATENT OFFICE.

WALTER D. BUTZ, OF NORRISTOWN, PENNSYLVANIA.

KNITTING MACHINE.

Application filed December 9, 1922. Serial No. 605,755.

My invention relates to that type of circular knitting machine in which the needle cylinder and needle dial are held against rotation, the cylinder cam ring and the dial 5 cam ring being the rotating elements. The object of my invention is to provide means for locking together the cylinder and dial without employment of the usual dogs on the inner face of the cylinder and the under face 10 of the dial, an object which I attain in the manner hereinafter set forth, reference being had to the accompanying drawings, in which—

Fig. 1 is a view, partly in side elevation and partly in vertical section, of sufficient 15 of a circular knitting machine to properly illustrate my invention,

Fig. 2 is a transverse sectional view on the line 2—2, Fig. 1, and

20 Figs. 3 and 4 are views similar to a portion of Fig. 2 but illustrating certain modifications of my invention.

Referring, in the first instance, to Fig. 1 of the drawings, there is illustrated a portion 25 of the fixed base 1 of a knitting machine to which is secured a non-rotating needle cylinder 3. Cooperatively positioned, in respect to this cylinder, is a non-rotating needle dial 4 mounted upon a central spindle 30 5 depending from an arch 6 which is carried by posts 7 secured to, and upwardly projecting from, a ring 8 to which movement of rotation is imparted by mechanism common to this type of knitting machine.

35 Secured to the ring 8 is a cylinder cam ring 9 provided with cams 10 adapted to operate the cylinder needles, the latter, for purposes of clarity, being omitted from the showing.

40 Above the needle dial 4, and rotatably mounted upon the spindle 5 is a dial cam ring 11 provided with cams 12 adapted to operate the dial needles. These needles, also, are omitted from the showing.

45 In order to insure proper co-rotation of the cylinder and dial cam rings 9 and 11, the latter is connected with the arch 6 in any suitable manner, as, for instance, by means of a post 13 secured, at its base, to the dial cam ring and having its upper end in engagement with the arch.

50 In order to provide for the proper immobility of the central spindle 5, while allowing necessary rotation thereabout of its supporting arch and the dial cam ring, the mechanism constituting the subject matter

of my present invention is provided and will now be described.

Secured to the upper face of the spindle 60 engaging hub of the arch 6, and rotatable therewith, is a disk 14, rotatable within a ring 15 formed upon an arm 16 adjustably engaged with an upstanding post 17 mounted, in any suitable manner, upon any available portion of the base 1 of the machine 65 or upon any portion of the fixed frame thereof. Other methods of adjustably mounting the ring 15 and its arm 16 will readily suggest themselves to the skilled knitter and need not be dwelt upon, here. 70

Secured to the spindle 5, above the disk 14, is a collar 18 upon which is vertically keyed or splined a disk 19 provided with a pair of notches 20 and 20^a (see Fig. 2) adapted for the reception of a corresponding 75 pair of bolt like terminals 21 and 21^a of an oscillatory member 22 pivotally mounted upon the arm 16. An outside bearing may be provided for the member 22 by making its periphery circular and by providing the up- 80 standing portion 15^a of the ring 15 with a corresponding segmental bearing portion 15^b.

Secured to, and rotatable with, the disk 14 is a cam 23 adapted to act, in turn, upon the bolts 21 and 21^a of the member 22. 85

Piercing the cam 23 and the disk 14 is a yarn feed aperture 24 through which the yarn passes on its way to the yarn guide 25, as shown in Fig. 1.

In operation, as the disk 14 and cam 90 23 rotate, the cam acts first upon the bolt 21, pushing it back out of the notch 20 to the position shown in Fig. 2, thereby permitting the yarn to be carried between the outer face of the disk 19 and the end of the bolt. At 95 the same time this is being effected, the oscillation of the member 22 causes the insertion of the bolt 21^a into the notch 20^a. It is this engagement of the disk 19 by the member 22, through the medium of its bolt, 100 which insures the necessary immobility of the central spindle 5.

Further rotation of the disk 14 and cam 23 brings the cam into contact with the bolt 21^a and pushes it back out of engagement 105 with the notch 20^a and clear of the path of the yarn. At this time the member 22 is reversely oscillated and the bolt 21 enters the notch 20.

The length of the bolts 21 and 21^a and 110 their degree of movement is such that the entering bolt is always in engagement with

its notch in the disk 19 before the departing bolt is free from its notch, so that, at no time, is the disk free from engagement by one or the other of the bolts of the member 22. Any accidental movement of the central spindle is thus rendered impossible.

By making the cam 23 double ended, as shown in Fig. 2, its rotation may be in either direction, or it may reciprocate, with equal facility.

In that modification of my invention shown in Fig. 3 the pivotal mounting feature of the engaging member is eliminated, the place of the member 22 being taken by a segmental member 32 adapted to fit within the bearing 15^b.

In the form shown in Fig. 4 a pair of radial bolts 31 and 31^a are used to cooperate with the notches in the disk 19. These bolts 20 are secured to and connected by a lever 42 which insures the proper synchronization of action.

Other modifications of my invention may readily be effected without departure from the essential features thereof and it is to be understood that I do not limit myself to any of the exact constructions which I have illustrated and described.

I claim:

1. The combination, in a knitting machine, of a needle cylinder, a needle dial, a dial supporting spindle, a suspension means therefor, a fixed member adjacent said spindle, a spindle locking member mounted upon said fixed member and having a plurality of synchronized locking elements, and means adapted to engage one of said locking elements for causing movement of said locking member to reversely move its locking elements.

2. The combination, in a knitting machine, of a needle cylinder, a needle dial, a dial supporting spindle, a suspension means therefor, a fixed member adjacent said spindle, an oscillatory spindle locking member mounted upon said fixed member and having a plurality of synchronized locking elements, and means adapted to engage one

of said locking elements for oscillating said locking member to reversely move its locking elements.

3. The combination, in a knitting machine, of a needle cylinder, a needle dial, a dial supporting spindle, suspension means therefor, a fixed member adjacent said spindle, a spindle locking member pivotally mounted upon said fixed member and having a plurality of synchronized locking elements, and means adapted to engage one of said locking elements for rocking said locking member about its pivot to reversely move its locking elements.

4. The combination, in a knitting machine, of a needle cylinder, a needle dial, a dial supporting spindle, suspension means therefor, a fixed member adjacent said spindle, a segmental bearing on said fixed member, a segmental spindle locking member seated in said bearing and having a plurality of locking elements, and means for oscillating said locking member in its bearing to reversely move its locking elements.

5. The combination, in a knitting machine, of a needle cylinder, a needle dial, a dial supporting spindle, suspension means therefor, a fixed member adjacent said spindle, a spindle locking member mounted upon said fixed member and having a plurality of synchronized locking elements, a cam adapted to engage said elements, alternately, and means for moving said cam.

6. The combination, in a knitting machine, of a needle cylinder, a needle dial, a dial supporting spindle, suspension means therefor, a fixed member adjacent said spindle, a spindle locking member mounted upon said fixed member and having a plurality of synchronized locking elements, a double faced cam adapted to engage said elements, alternately and in either direction, and means for moving said cam in either direction.

In testimony whereof I have signed my name to this specification.

WALTER D. BUTZ.
